United States Patent Office

Des. 195,377
Patented June 4, 1963

195,377

CLOSURE OR SIMILAR ARTICLE

Henry Wendland Franzreb and Howard Carl Hill, Easton,
Pa., assignors to American Can Company, New York,
N.Y., a corporation of New Jersey

Filed Dec. 19, 1961, Ser. No. 67,967

Term of patent 14 years

(Cl. D58—26)

Fig. 1.

Fig. 2.

We claim:

The ornamental design for a closure or similar article, substantially as shown and described.
